EVAN W. SWAIN AND OWEN E. SMITH, OF STOCKTON, CALIFORNIA.

STEERING MECHANISM FOR TRACTORS.

Application filed July 7, 1924. Serial No. 724,582.

To all whom it may concern:

Be it known that we, EVAN W. SWAIN and OWEN E. SMITH, citizens of the United States, residing at Stockton, county of San Joaquin, State of California, have invented certain new and useful Improvements in Steering Mechanism for Tractors; and we do declare the following to be a full, clear, and exact description of the same, reference being had to the accompanying drawings, and to the characters of reference marked thereon, which form a part of this application.

This invention relates to improvements in the steering mechanism of a certain type of tractor at present widely used. This tractor has no tiller or laterally steerable wheels, steering being effected by a braking action applied to the main transverse drive shafting of the tractor, to one side or the other of the differential mechanism interposed in such shafting.

The mechanism employed to attain this end includes brake drums mounted on the shafting split-end brake bands thereabout, the bands having end-lugs, a fixed bracket overhanging the lugs, and screws passing through the bracket and lugs, the turning of the screws one way or the other causing the bands to be tightened or loosened on the drums. The entire structure is mounted in a horizontally split housing, the upper portion of which is removable.

The linings on the bands sooner or later wear out, and need to be replaced.

As the mechanism is arranged at present, it is necessary to remove the upper part of the housing to enable the brake bands to be removed.

This operation of course disturbs the various gaskets between the housing sections, and these must frequently be renewed to maintain the necessary oil-tight joint.

Even after the housing member is removed, it is necessary to cut the rivets between the band and one of the end lugs before the band can be removed, since the clearance between the lower housing and the brake drum is not sufficient to enable the lugs to pass therearound. As a result, re-lining the bands, itself a simple and quickly accomplished job, requires a half-day's work or more on the part of a mechanic.

Having the above defects in mind, the

principal object of our invention is to eliminate the same by constructing and arranging certain of the parts so that to remove the bands, not only is it no longer necessary to cut the rivets between the lugs and bands as above stated, but the upper part of the housing need not be withdrawn. The said housing member is provided with an easily detached cover or manhole plate, and our device is so arranged that all operations can be carried out when this plate is removed. As a result of our device, the bands can be withdrawn, relined and replaced in but a fraction of the time previously necessary.

The parts of our structure are so designed that they merely take the place of the corresponding parts now used, without any alterations to the housing, or change in size of the brake drums or other mechanism or parts of the tractor being necessary.

A further object of the invention is to produce a simple and inexpensive device and yet one which will be exceedingly effective for the purposes for which it is designed.

These objects we accomplish by means of such structure and relative arrangement of parts as will fully appear by a perusal of the following specification and claims.

In the drawings similar characters of reference indicate corresponding parts in the several views:

Fig. 1 is a top plan outline of the transmission housing of a tractor, the upper part of the housing being broken away to show the transmission mechanism and our steering mechanism structure associated therewith.

Fig. 2 is a cross section on the line 2—2 of Fig. 1.

Fig. 3 is a sectional view of a composite brake-end unit.

Fig. 4 is a perspective view of the plate member of such unit.

Fig. 5 is a front end view of a composite steering-brake screw-bracket.

Fig. 6 is a fragmentary bottom plan view of the same.

Referring now more particularly to the characters of reference on the drawings, the numerals 1 and 2 denote the transmission housing members, the lower part 1 being fixed and the upper part 2 being removable. In this housing is mounted the driving axle

structure of the tractor, including a differential mechanism mounted in a casing 3, a master gear 4 alongside the same, and brake drums 5 on both sides of the differential mechanism.

Split bands 6 having the usual brake lining 7 are placed about the drums, tapped band-end lugs 8 being permanently fixed on the lower ends of the bands. The parts thus 10 far described are standard, and are not altered or disturbed in any way by our structure.

The latter comprises two separate features, both however being essential in attaining the results aimed at.

One of these features is the upper brake-end structure, a composite unit for each band, one part of which is a plate 9 following the contour of and permanently fixed 20 on the band and having a longitudinal slot 10 intermediate its ends, said slot thus extending circumferentially of the band. The other part of said unit is a lug 11 vertically bored in alinement with and above the lug 8. 25 Formed with this lug is a plate 12 having a close fit in the slot 10 and having an extension 13 at its upper end overlapping the plate 9 beyond the upper end of the slot and secured to said plate by removable cap 30 screws 14.

The two parts are thus locked together to form a rigid unit, in which the contacting end-faces of the plates 9 and 12 take all the strain, the cap screws merely holding 35 the parts against displacement.

The other feature of our structure is the steering brake-screw bracket, also a composite unit, which takes the place of the one-piece bracket heretofore used.

40 This unit comprises end pedestals 15 resting on the side flanges of the lower housing member 1, and secured thereto by bolts 16 which use the same holes already provided for holding the original bracket in place.

45 Vertical grooves 17 are formed in the adjacent faces of the pedestals serving as guides for tongues 18 formed on the opposed end faces of a bridge 19. This bridge has pads 20 which rest on top of the pedestals, being secured thereto by detachable cap 50 screws 21. The bridge, adjacent its opposite ends, is drilled from top to bottom as at 22, to receive the usual steering screws 23 which pass through the lugs 11 and 8, 55 and are screwed into the latter.

The upper faces of the lugs 11 bear against the lower face of the bridge when any clamping strain is thrown onto the brake bands.

60 In operation, to remove the bands, the cover plate 24 of the upper housing 2 is first removed, this cover being above the bracket and band-ends. Removal of this cover thus enables the screws 23 to be withdrawn, after which the screws 21 are taken

out, when the bridge may be removed by raising the same vertically from the pedestals until the tongues 18 clear the grooves 17.

The upper band end unit is then fully exposed, and after the screws 14 are removed, the lug 11 may be withdrawn from the plate 9. This leaves the band 6 with only a slight projection above its outer surface which the housing about the brake drum will clear. Removal of the lug 11 exposes the lower lug 75 8, which is then grasped and pulled upwardly by the worker, causing the band, which of course is flexible, to be moved around its drum and to be withdrawn from between the drum and housing. The lining 80 of the band may then be easily renewed, and the band is reinserted by a reversal of the movement necessary to withdraw the same, as above described, and the other parts 85 replaced in order.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 95 claims.

Having thus described our invention what we claim as new and useful and desire to secure by Letters Patent is:

1. In combination with a brake drum mounted in a housing, and a split-end band about the drum, and a lug structure on one end of the band, a bracket structure mounted in the housing and overhanging the lug, there being insufficient clearance between the 100 drum and housing to permit the lug to pass therebetween, and means provided with the lug and bracket structure for enabling the band to be withdrawn from about the drum without lateral deflection of the band and without disturbing the drum and housing.

2. In combination with a brake drum mounted in a housing, and a split-end band about the drum, a readily detachable lug on one end of the band, a bracket structure mounted in the housing and overhanging the lug, the band being only removable upon the removal of the lug, and a detachable member incorporated with the bracket structure and disposed to permit free access to the lug 115 from above being had when said detachable member is removed, to then allow the lug to be removed.

3. In combination with a brake drum mounted in a housing, and a split-end band about the drum, a band-end unit on one end of the band, said unit comprising a fixed plate and a removable lug mounted in connection therewith, the band being only removable upon removing the lug, a bracket 120

structure mounted in the housing and having a part overhanging the lug, and means provided with said structure for enabling free access to the lug from above being had, to 5 permit of the removal of said lug.

4. In combination with a brake drum mounted in a housing, and a split-end band about the drum, a band-end unit on one end of the band, said unit comprising a fixed 10 plate and a removable lug mounted in connection therewith, the band being only removable upon removing the lug, and a bracket structure mounted in the housing, said structure including a detachable member 15 overhanging the lug and against the under face of which the lug is adapted to bear.

5. In combination with a brake drum mounted in a housing, and a split-end band about the drum, a readily detachable lug on 20 one end of the band, a bracket structure mounted in the housing and overhanging the lug, and having a detachable member formed therewith, means whereby the band can be removed only by detaching the lug, 25 and means whereby said lug can only be detached by removing the detachable bracket member.

6. In combination with a brake drum mounted in a housing, and a split-end band 30 about the drum, a lug structure on one end of the band, a bracket structure mounted in

the housing, said structure comprising end pedestals permanently mounted in the housing, the lug projecting therebetween, and a bridge supported on and removably connected to the pedestals, the lug being adapted 35 to bear against the under face of the bridge.

7. In combination with a brake drum mounted in a housing, and a split-end band about the drum, a lug structure on one end of the band, a bracket structure mounted in the housing, said structure comprising end pedestals permanently mounted in the housing, the lug projecting therebetween, a bridge extending between the pedestals and 40 having end pads resting thereon, and vertical tongue and groove means between the adjacent faces of the pedestals and bridge, whereby to hold the parts in alinement and permit the withdrawal of the bridge from 45 the pedestals by an upward movement.

8. In combination with a brake drum mounted in a housing, a split-end band about the drum and a lug mounted on one end of the band; a removable member in the housing overhanging the lug and against which the latter bears. 50

In testimony whereof we affix our signatures.

EVAN W. SWAIN.
OWEN E. SMITH.
